COMBINED TAIL-LIGHT LENS AND MOUNTING BASE THEREFOR

Hugo Magi, Etobicoke, Ontario, Canada, assignor to
Dominion Auto Accessories Limited, Toronto,
Ontario, Canada

Filed Mar. 10, 1969, Ser. No. 16,159

Term of patent 14 years

Int. Cl. D12—99

U.S. Cl. D48—32

FIG.4.

FIG.3.

FIG.5.

FIG. 1 is a perspective view of a combined tail-light lens and mounting base, therefor showing my design, seen from slightly above and to one side;

FIG. 2 is a perspective view of the device of FIG. 1, seen from slightly below and to the other side;

FIG. 3 is an elevational view of the device of FIG. 1; FIG. 4 is an end view of the device of FIG. 1; and FIG. 5 is a top view of the device of FIG. 1.

I claim:

The ornamental design for a combined tail-light lens and mounting base therefor, as shown and described.
